S.H. CAMPBELL

BY *E. C. Huppman*
ATTORNEY

UNITED STATES PATENT OFFICE.

STERLING H. CAMPBELL, OF ST. LOUIS, MISSOURI, ASSIGNOR TO WESTERN RAILWAY EQUIPMENT COMPANY, OF ST. LOUIS, MISSOURI, A CORPORATION OF MISSOURI.

FLOOR CONSTRUCTION.

Application filed July 5, 1924. Serial No. 724,288.

My invention relates to floor securing means for railway cars of the general type described in Pratt United States Patent No. 1,498,119 in which the securing means does not pass through the floor sill.

The object of the present invention is to provide means for preventing relative rotary movement between the bolt and clip, the bolt itself being non-rotary in the floor board, so that the clip is held in proper relation without depending either on the contact of the clip with either the edge of the sill flange or with the floor board.

In the accompanying drawings which illustrate two forms of floor construction made in accordance with my invention, Figure 1 is a vertical cross section through a portion of a railway car to which my device is applied; Figure 2 is a detail view of the clip; Figure 3 is a sectional view similar to Figure 1 but showing a modification; and Figure 4 is a detail view of the form of clip shown in Figure 3.

Referring first to Figures 1 and 2, 5 indicates a center sill of a car upon the horizontal flange 6 of which is supported a floor board 7. At some distance from the edge of the flange 6 the floor board has formed therein a bolt hole 8 terminating at its upper end in an enlargement 9. Extending upwardly through the bolt hole 8 is a bolt 10 having a square or other non-circular portion 11 adjacent to its head 12. This square portion 11 is adapted to be drawn up into the floor board and also engages with a correspondingly shaped opening 13 in the clip 14. As shown in Figure 2, this clip is rectangular in shape and has one edge 15 bent down out of the plane of the body of the clip so as to engage with the under face of the flange 6. The engagement of the square portion 11 of the bolt with both the floor board and the square opening 14 in the clip prevents both the rotation of the bolt with respect to the board and the rotation of the clip with respect to the bolt and consequently the clip is retained in proper relation to the sill. A nut 16 in the enlargement 9 of the bolt hole engages with the threaded end of the bolt. This nut preferably bears on a washer 17 and the end of the bolt is provided with a slot 18 so that it may be spread to form a nut lock.

In Figures 3 and 4 I have shown a modification in which the bolt 20 has a square

portion 21 of sufficient length to pass through the floor board and project a slight distance below the same. The projecting square portion engages with an opening 22 in the clip 23. The clip 23, as shown in Figure 4, is substantially triangular in shape and is provided with a downwardly bent edge 24 for engaging with the under face of the flange 6. A nut 25 engages the threaded end of the bolt and the end is split at 26 to form a nut lock.

It will be evident that in both the constructions set forth the bolt is held from rotation in the floor board and the clip from rotating on the bolt and that consequently the clip will be held in proper relation to the sill without any means on the clip for engaging either with the edge of the sill or with the floor board to prevent rotation.

Having fully described my invention, what I claim as new and desire to secure by Letters Patent of the United States is:

1. In a device of the class described, the combination with a floor sill, of a floor board supported on said sill, a retaining clip overlapping the sill and having a portion bearing on the board, and a bolt extending through said board and clip and provided with a non-circular part, said non-circular part extending into both the board and clip to prevent their relative rotation.

2. In a device of the class described, the combination with a floor board provided with a non-circular aperture, of a retaining clip overlapping the sill and having a part lying against the board and provided with a corresponding non-circular aperture, and a bolt securing said clip to said board and having a non-circular part entering both said non-circular apertures to prevent the relative rotary movement of the board and clip.

3. In a device of the class described, the combination with a floor sill, of a floor board supported on said sill, a bolt extending through said board and provided with a non-circular part adjacent to the head, said non-circular part preventing rotation of the bolt in the board, and a clip surrounding said bolt adjacent to the head and cooperating with the non-circular part to prevent rotation, said clip engaging with the sill.

In testimony whereof, I have hereunto set my hand this the 2nd day of July, 1924.

STERLING H. CAMPBELL.
